UNITED STATES PATENT OFFICE.

LORENZO D. HORNBECK, OF PAXTON, ILLINOIS, ASSIGNOR OF ONE-HALF
TO JAMES S. GRAHAM, OF SAME PLACE.

NECK-YOKE.

SPECIFICATION forming part of Letters Patent No. 270,802, dated January 16, 1883.

Application filed November 8, 1882. (No model.)

To all whom it may concern:

Be it known that I, LORENZO D. HORNBECK, a citizen of the United States, resident of Paxton, in the county of Ford and State of Illinois, have invented a new and valuable Improvement in Neck-Yokes; and I do hereby declare that the following is a full, clear, and exact description of the construction and operation of the same, reference being had to the annexed drawings, making a part of this specification, and to the letters and figures of reference marked thereon.

Figure 1 of the drawings is a representation of this invention in a perspective view. Fig. 2 is a perspective detail view, showing the forked bearing. Fig. 3 is a vertical section taken through one of the thimble-irons and the end of the neck-yoke bar to which it is attached.

This invention has relation to anti-friction connections for the ends of neck-yoke bars; and it consists in the construction and novel arrangement of the bifurcated thimble-iron and the double-forked bearing pivoted in the fork of the thimble-iron, and having laterally-separated roller-bearings extending between the branches of the forked bearing, all as hereinafter set forth, and particularly pointed out in the claim appended.

In the accompanying drawings, the letter *a* designates the transverse neck-yoke bar, to the ends of which the thimble-irons *b* are attached. These thimble-irons may be internally threaded to engage the ends of the neck-yoke bar; or they may be fastened by means of pins passing through suitable perforations. The outer end of each thimble-iron is bifurcated, the upper and lower branches of the fork being parallel on their inside faces. These branches are also perforated for the passage of a strong pivot-pin, *c*.

d represents the double-fork bearing, consisting of a body portion, *e*, and the upper and lower forked branches, *g* and *h*. Each branch

is also constructed with branches or arms, which are laterally arranged in such relation 45 that the arms of the upper branch are over the arms of the lower branch. The ends of the arms are perforated to receive the connecting-pins bearings *k*, on which the rollers *l* are placed. These rollers are therefore held between the arms of the branches of the pivoted bearing in lateral relation to each other, their position being always at right angles to the direction of the length of the neck-yoke bar, although the bearing *d* has vibratory motion 55 from side to side on the pivot-pin *c* of the thimble iron. As the body portion *e* of the forked bearing *d* is constructed with plane upper and lower surfaces to fit the bifurcation *m* of the thimble-iron neatly, all oblique or wabbling 60 motion in the connection is avoided, the bearing being held in true relation to the neck-yoke bar. This construction also serves to prevent rattling of the parts when the horses are moving forward, and when backing or going down hill 65 enables the breast-straps to adjust themselves automatically in proper relation to the roller-bearings *l* without catching on the connecting-frame or getting awry in any way.

Having described this invention, what I 70 claim, and desire to secure by Letters Patent, is—

The neck-yoke connection consisting of the bifurcated thimble-iron *b* and the double-forked bearing *d*, pivoted in the fork of the thimble-iron, and having laterally-separated 75 roller-bearings *l* between the branches of the forked bearing, substantially as specified.

In testimony that I claim the above I have hereunto subscribed my name in the presence 80 of two witnesses.

LORENZO DOW HORNBECK.
